UNITED STATES PATENT OFFICE.

HERBERT L. MERRICK, OF PASSAIC, NEW JERSEY.

MATERIAL-FEEDING MEANS.

Application filed August 13, 1924. Serial No. 731,711.

This invention relates to means for feeding material in predetermined quantities, as by measure or weight, for use in feeding aggregates or component parts of a composition of matter or association of parts, such as the feeding of aggregates in cement making to a point or place where they are to be subjected to treatment to be reduced to a pulverized state, and it is an object of the invention to provide improved means for this purpose which is adapted to feed variable predetermined quantities of material at a constant rate or intermittently at predetermined intervals.

It is another object of the invention to provide weighing mechanism for this purpose whereby the material while being transported, as by a conveyor, from a source of supply to its place of use is weighed and effecting the delivery of a predetermined uniform quantity of material per unit of conveyor length for a given unit of time and the constant speed of travel of the conveyor by controlling the discharge or feeding of material from a hopper to the conveyor.

It is a further object of the invention to provide improved means for regulating the discharge of material from a hopper to a travelling conveyor controlled by weighing mechanism arranged to support a portion of the conveyor with a load being transported thereby, such regulating means for the discharge of the material being controlled by and in accordance with the deflection of the weighing beam without interference with the movement or loading of said beam.

It is another object of the invention to provide an adjustable closure for the outlet of a hopper with regulatable means for said closure to vary the discharge of material from said hopper to a travelling conveyor controlled by and in accordance with variations in the load carried by the conveyor through an axial movable rotatable member having connection with the closure and the axial direction of travel of said rotatable member being controlled by and in accordance with the movement of the weighing mechanism to overload or underload position by variations in the load transported by the conveyor.

Another object of the invention relates to means for feeding materials from different

sources of supply to a common place of use and the delivery of said materials in predetermined variable proportional quantities one relative to the other with means to control the delivery of one quantity of material by the delivery of a predetermined quantity of another material.

A further object of the invention relates to the provision in material carrying conveyors of means operable to control the quantity of material delivered by one conveyor in predetermined proportion to the quantity of material delivered by another conveyor.

It is a further object of the invention to provide material feeding means including a pair of conveyors and weighing mechanism to determine the load transported thereby, with means to determine the load transported by one conveyor by the rate of speed of travel of the conveyor and the load transported thereby, and said means being operative when a predetermined quantity of material has been transported over the weighing mechanism to set another conveyor in operation, and the quantity of material transported by said latter conveyor being controlled by the load thereon by the weighing mechanism associated therewith, the quantity of material delivered by said latter conveyor being in predetermined proportion to the quantity of material delivered by the first conveyor.

Other objects and advantages will herein-after appear.

In carrying out the invention I provide a conveyor, such as an endless belt, to transport material delivered thereto from a suitable source, such as a hopper having an outlet arranged in superposed relation thereto, the material discharged from the hopper being regulated by an adjustable closure or gate to vary the area of the hopper outlet, and the adjustment of such closure being effected automatically by and in accordance with the load or quantity of material upon the conveyor. To adjust said closure a weighing beam is provided arranged with means to support a portion of the conveyor, and the deflection of the weighing beam controlling the extent and direction of movement of an axially movable rotatable member having connection with the closure for the hopper outlet to position said closure to regulate

- the area of the hopper outlet, the movement of said rotatable member being controlled by a member having frictional contact therewith and traveling normally in a direction 5 substantially at right angles to the axis of the rotatable member and adapted to be adjusted by and in accordance with the deflection of the weighing beam to change the direction of travel thereof in angular relation 10 to the axis of the axially movable member and thereby exert a thrust upon said axially movable member to move the same axially the direction of travel of said axially movable member being controlled by the angular 15 relation of the friction travelling member to the axially movable member and the deflection of the beam to overload or underload position.

To feed one material from a source of 20 supply to the place of use in predetermined proportion to the feeding of another material from a source of supply to the place of use there is provided a second conveyor with weighing mechanism arranged to suspend 25 and support a portion of the conveyor therefrom, said conveyor preferably being driven at a constant rate of speed and the weight of the transported load determined by integrating means operative by the rate of speed 30 of the conveyor and the load transported thereby, means being provided which is operative when a predetermined load has been transported by the conveyor to said means in operation to actuate the other conveyor 35 mechanism, and set means being operative to stop said conveyor mechanism after a predetermined length of travel of the conveyor.

In the drawings accompanying and forming 40 a part of this specification there is shown an embodiment of the invention wherein Figure 1 is a perspective view looking at the side and from the front of the means for regulating the delivery of material to one conveyor to feed variable predetermined loads, only a portion of the conveyor means being shown.

Figure 2 is a plan view of the feeding means shown in Figure 1.

Figure 3 is a side elevation of the mechanism shown in Figure 2 with the driving means for the conveyor removed.

Figure 4 is a perspective view of the feeding means shown in Figure 1 looking at the side and rear.

Figure 5 is a cross sectional view taken substantially on the line 5—5 of Figure 8 looking in the direction of the arrows.

Figure 6 is a perspective view of the gearing shown in Figure 5 for adjusting the counterpoise relative to a weighing beam of the weighing mechanism and for adjusting the closure for the outlet of a hopper for delivering material to the conveyor.

Figure 7 is a perspective view looking at

the rear and side opposite to that shown in Figure 4 with the conveyor and the hopper for delivering material to the conveyor removed.

Figure 8 is a side elevation of the mechanism shown in Figure 1 and showing in addition thereto the hopper for delivering the material to the conveyor and showing the manner of supporting a portion of the conveyor from a weighing beam.

Figure 9 is a perspective view of a weighing lever or beam from which to support a portion of the material carrying conveyor and showing in section counterpoise weight 75 adjustably mounted on the beam for adjusting the same to counterbalance variable predetermined loads carried by the conveyor.

Figure 10 is a cross sectional view taken substantially on the line 10—10 of Figure 9 looking in the direction of the arrows.

Figure 11 is an end elevation looking at the left of Figure 2 and showing the conveyor in section.

Figure 12 is a perspective view of change speed gearing for driving the conveyor at different speeds.

Figure 13 is a perspective view to show the manner of suspending a portion of the conveyor from the weighing beam shown in Figure 9.

Figure 14 is a side elevation, partly in section, of the change speed gearing shown in Figure 12 to show the manner of meshing different gears to drive the conveyor at different speeds.

Figure 15 is a side elevation of a friction driven drum forming a part of means to adjust the closure for the outlet of the hopper from which material is delivered to the conveyor shown in Figure 8, the same being 105 shown partly in section to show the mounting thereof on a shaft to permit of longitudinal movement of the drum while participating in the rotative movement of the shaft.

Figure 16 is a cross sectional view taken substantially on the line 16—16 of Figure 15 looking in the direction of the arrows.

Figure 17 is a disassembled view, partly in section, of the right hand end of the drum 115 shown in Figure 15 to show the means and manner of mounting the drum upon its support and rotating shaft.

Figure 18 is an end elevation, partly broken away, to show the driving means for the drum carrying shaft shown in Figure 15 and to actuate a limit switch.

Figure 19 is a sectional view in side elevation of the driving means shown in Figure 18 looking at the right thereof and showing the drum supporting shaft in relation thereto.

Figure 20 is an end elevation, partly in section, of differential driving gearing forming a part of the gearing shown in Figure 6.

Figure 21 is a cross sectional view taken substantially on the line 21—21 of Figure 20 looking in the direction of the arrows.

Figure 22 is an end elevation of a limit switch used in connection with the feeding means with a portion of the enclosing housing therefor removed.

Figure 23 is a side elevation of the time switch shown in Figure 22 looking at the left of said figure with the enclosing housing therefor in section.

Figure 24 is a plan view showing in a diagrammatic manner an installation of the feeding apparatus for feeding one material in predetermined proportional relation to the feeding of a quantity of another material.

Figure 25 is a front elevation of weighing mechanism arranged to suspend and support a portion of one of the conveyors shown in Figure 24 and having combined therewith integrating means for determining the quantity of material transported by the conveyor by the speed rate of travel of the conveyor and the load carried thereby; and

Figure 26 is a diagrammatic view of an electric circuit means controlled by the integrating means of one feeding means to control the actuation of the time switch and the actuating of the other conveyor.

Similar characters of reference designate like parts throughout the different views of the drawings.

In the embodiment of the feeding mechanism shown in Figures 1 to 23 inclusive, the material handling conveyor comprises an endless belt B passing around a pair of drums 27, 27' journaled in bearings 28, 28' mounted on sills 29, 29' of the framework to travel in the direction of the arrow, and to one of which drums, in the present instance the drum 27, driving means, such as an electric motor M, is operatively connected in a manner and for a purpose to be hereinafter described. The drum bearings 28 are fixed upon the sills while the sills 28' for the drum 27' are mounted to have adjustment in a direction to move the drum toward and away from the drum 27. The bearings 28' with the drum are urged in a direction away from the drum 27 by a counterweight 30 suspended from one end of a cable 31 passing over a sheave 32 and the opposite end connected to a sheave 33 fixed to a shaft 34 journaled in bearings upon the sills. The counterweight is connected to the drum bearing 28' by cables 35 connected at one end to the bearings 28' and the opposite ends connected to sheaves or drums 36 on the shaft 34. The movement of the drum bearings 28' is limited by stops 37. The cables 35 may be arranged with turn buckles to extend or shorten the same. By this arrangement the conveyor belt while maintained taut is permitted to have yielding movement

to compensate for the movement of the load carrying portion of the upper stretch of the conveyor with the result that there will be no possibility of introducing inaccuracies in the operation of the mechanism due to variations in the load transported by the conveyor and consequent pulling strain upon the conveyor. The upper stretch of the conveyor is also supported by rollers 38 rotatably carried by standards fixed to and extending upward from the sills, and a portion or section of the conveyor intermediate a pair of said rollers is suspended by a roller 39 rotatably carried at the ends by a pair of links 40 pivotally suspended from lever arms 41 rigid with a rocker bar 42 pivotally supported upon standards 43 (Figures 1, 2, 3 and 13) fixed upon a standard in the form of a shelf 43 superposed to the conveyor. The arms 41 extend laterally of and in parallel relation to the conveyor and in a direction opposite to that in which the conveyor travels. The rocker bar 42, arms 41, links 40 and roller 39 form a part of means to counterbalance the load upon the conveyor, which is in the nature of weighing mechanism, for a purpose to be hereinafter described.

The material to be fed by the conveyor is delivered thereto from a hopper H having an outlet arranged in superposed relation to the conveyor with guide ports 45 (Figures 2, 3 and 8) extending forwardly from said outlet in the direction of travel of the conveyor from opposite sides of the hopper outlet above and in contiguous relation to the conveyor and within the lateral edges thereof to prevent material from spilling from the sides of the conveyor as the material is delivered thereto from the hopper, as clearly shown in Figure 2. An adjustable closure in the form of a gate 46, is provided for the hopper outlet to regulate the area thereof and discharge of material from the hopper, said closure being mounted at opposite ends in slideways formed in the opposite walls of the hopper to have vertical sliding movement.

To handle and feed a predetermined quantity of material by the conveyor, and to vary said quantity at will, means are provided to automatically adjust the closure to vary the area of the hopper outlet and regulate the discharge of material from the hopper to the conveyor to handle a predetermined uniform quantity of material by the conveyor per unit of conveyor length for a given unit of time with a constant speed of travel of the conveyor and the load carried by the conveyor. For this purpose there is provided a lever 47, herein termed a weighing beam, fulcrumed at 48 upon the superstructure 44 having the shorter end connected to the rocker bar 42 by a link 49 connected to a lever arm 50 rigid with the rocker

bar 42 and extending therefrom in parallel relation to the arms 41 thereby suspending a portion of the load therefrom through the conveyor supporting roller 39 suspended from the rocker arms 41 by the links 40. The one end of the weighing beam may be arranged with a compensating weight support 50', and to counterbalance a load of predetermined weight upon the conveyor by the weighing beam counterpoise weight 51 is adjustably mounted upon the beam, this counterpoise weight being in the form of a carriage to overhang the sides of the beam and supported upon the beam by rollers 52, the beam being of U-shape in cross section with the edges of the opposite legs serving as tracks for the carriage rollers, as clearly shown in Figure 9. To prevent undue vibration of the beam as it is brought to equilibrium by the load on the conveyor a dash pot 53 is provided the movable member of which is connected to the beam, as at 54. (Figures 1, 3, 7 and 8). To prevent undue deflection of the weighing beam by an overload or underload on the conveyor auxiliary counterpoise weight is provided normally free of the beam and adapted to be applied to or picked up by the beam. This auxiliary counterpoise weight comprises a pair of counterweighted levers 54', 54'' pivotally supported at 55, the counterweight being so arranged as to normally assume a position below the center of gravity. (Figure 8.) The levers 54', 54'' pivotally carry supplemental counterweight levers 56, 56'. A rod 57 suspended from the weighing beam is arranged with a pair of hooks 58, 58', the hook 58 being adapted to pick up and apply the supplemental counterpoise with the lever 56 to the beam and through said lever upon further deflection of the beam apply the auxiliary counterpoise weight lever 54' to the beam when the beam is deflected downward or to underload position, while the hook 58' is adapted to pick up and apply the supplemental counterpoise weight lever 56' to the beam and through said lever apply the auxiliary counterpoise weight lever 54' to the beam when the beam is deflected upward or to overload position. It will be obvious that as the beam is brought to equilibrium it will be relieved of the weight of said auxiliary and supplemental counterpoise weight. The position of the counterpoise weight 51 upon the weighing beam is in accordance with the required or determined quantity of material to be handled or fed by the conveyor to counterbalance such load, and the quantity of material to be fed by the conveyor may be variable and changed at will by the adjustment of the counterpoise upon the beam.

To maintain the load transported by the conveyor at a constant predetermined value to counterbalance the weight of the counterpoise upon the beam, the position of which counterpoise weight upon the beam is in accordance with the weight of such predetermined load, means are provided to adjust the closure 46 for the hopper outlet to vary the area thereof to increase or decrease the discharge of material from the hopper to the conveyor by a variation in the load transported by the conveyor and the moving of the weighing beam out of equilibrium by an underload or overload upon the portion of the conveyor supported by said beam. This means comprises a rack 60 fixed to the gate 46 to extend in a vertical direction and meshing with a pinion 61 fixed to a shaft 62 of differential gearing carried in a housing or casing C (Figures 20 and 21) fixed upon the framework and in which casing the shaft 62 is journaled and has a head 63 fixed thereto within the casing, said head carrying a pair of pinions 64, 64' to rotate on axes arranged eccentric to the axis of the shaft 62 and diametrically opposite to each other, said pinions meshing with a pinion 65 fixed to a shaft 66 journaled coaxially with the shaft 62 in the hub of a head 67 rotatably supported in the casing in concentric relation to said shaft, said head carrying an internal gear 68 with which the pinions 64, 64' also mesh for the purpose of allowing a hand wheel to simultaneously adjust the closure gate of the hopper and the counterpoise weight on the scale beam as is fully described hereinafter. A gear 69 fixed to the shaft 66 meshes with a rack 70 fixed at opposite ends to a pair of heads 71, 71' connected in spaced relation to a connecting member 72 (Figure 15), said heads and connecting member constituting a carriage for a drum 73 supported at opposite ends in the carriage heads to have rotative movement. Each carriage head rotatably carries flanged rollers or wheels 74 whereby the carriage with the drum is mounted upon the rails 75 carried by standards 76 fixed upon the support 44 for the weighing mechanism to have movement to and fro longitudinally of said means and by means of which movement the closure for the hopper outlet is adjusted through the gearing just described.

The drum 73 is continuously rotated and simultaneously with the rotation thereof adapted to have longitudinal movement imparted thereto. For this purpose there is provided a shaft 77 of rectangular shape in cross section journaled at opposite ends in standards 78 fixed upon the support or shelf 44. This shaft extends through the drum and is mounted concentrically or axially of the drum by heads 79 engaging in the ends of the drum and whereby the drum and shaft 77 are rotatably supported in the carriage heads 71, 71'. The drum supporting heads 79 also serve as carriers for anti-friction bearings for the drum upon the shaft, said bearings consisting of flanged rollers

80, a pair of said rollers engaging at opposite sides of the shaft with the rollers at one end of the drum arranged to engage with the shaft in angular relation to the 5 rollers at the opposite end of the drum. The rollers 80 are mounted in opposite recesses 81 in the drum carrying heads and retained therein by releasable caps 82 (Figure 17). The drum is rotated from the 10 motor M by a sprocket chain 83 (Figures 2, 8, 11, 12, 18 and 19) passing around a sprocket wheel on the motor shaft and a shaft 84, and a sprocket chain 85 passing around a second sprocket wheel on shaft 84 15 and a sprocket wheel 86 on a shaft 87 with a gear 88 on said latter shaft meshing with a pinion 89 on the drum carrying shaft 77. The adjustment of the closure or gate 46 for the hopper outlet is effected through 20 the longitudinal movement of the drum and the drum rack 70 meshing with the gear 69 connected with the gate through the differential gearing in gear casing C, and longitudinal movement of the drum is effected 25 by and in accordance with variations of the load on the conveyor and the moving of the weighing beam out of equilibrium by an underload or overload on the conveyor and maintained against movement when the 30 beam is in equilibrium. For this purpose a friction traveling member in the form of a disk 90 frictionally contacts with the drum (Figures 1, 2, 3, 5, 8 and 11). This disk is mounted in a bifurcation 91 of a yoke shaped 35 carrier 92 to rotate on a horizontal axis, and the disk carrier having oppositely extending studs 92', 92'' (Figures 7 and 8) whereby it is mounted to have movement on an axis transverse to the axis of the disk in a portion 40 of a bracket 93 overhanging the drum and a portion extending below the drum, said bracket being fixed upon the shelf 44. The disk is maintained in contact with the 45 drum by gravity by the weight of the disk and its carrier and is frictionally driven from the drum. When said disk is traveling in a direction at right angles to the drum it will operate to hold the drum 50 against longitudinal movement. However, when the direction of travel of the disk is changed in angular relation to the axis of the drum it will exert a thrust upon the drum to move it axially, the direction of the 55 movement of the drum being in accordance with the angular relation of the disk to the drum. The direction of travel of the disk is controlled by the position of the weighing beam 47 effected by the load upon the conveyor. The disk is connected to the weighing 60 beam to effect changes in the direction of travel thereof by the deflection of the beam by a link 94 pivotally connected at one end with the stud 92'' of the disk carrying yoke and an arm 95 rigid with and ex- tending downward from the weighing beam in line with the axis of the pivotal support of the beam. Should there be an overload upon the conveyor thereby deflecting the weighing beam upward the friction disk 70 support and thereby the disk will be adjusted to travel in a direction in angular relation to the axis of the drum to exert an axial thrust upon and move the drum 75 axially in the direction of the arrow indicated in Figures 1, 2 and 6, and thereby through the gearing connection of the drum with the gate move the gate in a direction to reduce the area of the hopper outlet and a consequent reduction in the discharge of 80 material from the hopper to the conveyor, such adjustment of the gate being effected until the load on the conveyor is such as to bring the weighing beam into position of 85 equilibrium. When the load on the conveyor is under that of a predetermined weight, this being determined by the positioning of the counterpoise weight upon the beam, and the long end of the beam is deflected downward the friction disk will be 90 adjusted to travel in a direction in angular relation to the drum to cause it to be moved in a direction opposite to that indicated by the arrow in Figures 1, 2 and 6 effecting 95 movement of the closure gate for the hopper outlet to increase the area thereof and an increased discharge of the material from the hopper to the conveyor, this increased discharge being continued until the beam is again brought into equilibrium by the load upon the conveyor. From the foregoing it will be obvious that a load of a predetermined weight will be constantly fed and delivered by the conveyor, and the weight 100 of the load and the quantity of material fed by the conveyor will be in accordance with the position of the counterpoise weight upon the weighing beam. Means are provided to adjust the counterpoise weight upon the weighing beam and to simultaneously adjust the closure for the hopper outlet to vary the area of said outlet in proportional relation to the position of the counterpoise upon the beam, said means 110 comprising a hand wheel 96 (Figures 1 to 6) arranged at the front side of the apparatus and fixed to a shaft 97, said shaft being operatively connected to effect movements to a counterpoise adjuster to move the counterpoise along the weighing beam. The counterpoise adjuster comprises an arm 99 carrying flanged rollers 100 whereby it is mounted upon a slideway 101 to extend in a vertical direction and have movement in a 115 direction in a plane longitudinally of the weighing beam, the arm 99 being connected to the counterpoise by a rod 101'. Movement of the counterpoise adjuster along the slideway 101 is effected through the rotation 120 of the hand wheel 96 by a rack 102 connected 125 130

at one end to the adjuster arm 99 and the opposite end connected to a head 99' carrying a pair of rollers 100' whereby it is mounted upon a slideway 101'', the rack being connected to the hand wheel by a train of gearing consisting of a gear 102' fixed to shaft 97, a gear 103 in mesh with the rack and intermediate pinions 104, 105 meshing with the gears 103 and 102 respectively. By the arrangement of the gearing as the hand wheel is rotated to the right the counterpoise will be adjusted to the right or outward on the beam, and when said wheel is rotated in reverse direction the counterpoise will be adjusted in opposite direction on the beam. To simultaneously adjust the closure for the hopper outlet with the adjustment of the counterpoise weight there is provided a gear 106 on shaft 97 which meshes with a gear 107 fixed to the hub of the carrier 67 for the pinions 64 of the differential gearing in casing C (Figure 21,) whereby the rotation of the shaft 62 carrying the pinion 61 in mesh with the closure rack 60 is effected simultaneously with the rotation of the hand wheel.

As stated the conveyor is driven from the motor M and to effect variations in the rate of speed of travel of the conveyor and thereby effect variations in the load handled by the conveyor, variable speed driving means for the conveyor is provided. The embodiment of this driving means shown in the drawings (Figures 12 and 13) comprises a worm 108 on the motor shaft meshing with a worm wheel 109 on a shaft 110 which may constitute the motor shaft if desired. A gear 111 and a pinion 112 are mounted on the shaft 110 to rotate therewith and have movement along the shaft in unison and adapted to mesh with a pinion 113 and a gear 114, respectively, on a shaft 115. When the pinion 112 is in mesh with gear 114 the gear 111 will be out of mesh with pinion 113 and vice versa. The shaft 115 is connected to the conveyor drum 27 by a worm 116 meshing with a worm wheel 117 on a shaft 118 having a flexible coupling with the drum shaft. The reducing gearing 50 may be enclosed in a housing 119 as shown in Figure 2.

To indicate the weight of the material fed by the conveyor per unit of length of travel of the conveyor a scale beam 119' is provided suitably calibrated or graduated relative to which an indicator 120 is moved simultaneously with the adjustment of the poise weight 51 on the weighing beam, this indicator being mounted upon the head 99' to participate in the movement imparted thereto by the hand wheel 96. It will be obvious that when the conveyor is traveling at one rate of speed the quantity of material fed will be different than when the conveyor is traveling at another rate of speed, and

a multiple calibrated or graduated scale beam is therefore provided. For this purpose the scale beam 119' is of rectangular shape in cross section and is pivotally supported at opposite ends in brackets 121, 122 fixed to the framework, the bracket 122 also being arranged to slidably support a rack 123 with which a pinion 124 carried by the scale beam meshes. While calibrations may be arranged on the four sides of the scale beam, in the present instance where only two changes in the rate of speed of travel of the conveyor may be effected only two of the sides are calibrated. Adjustment of the change speed gears 111, 112 is effected by a pivotally supported hand lever 125 to the support of which an arm 126' is fixed to participate in the movement of the lever and whereby the lever is connected by a link 127 to an arm 128 of a rock shaft 129 (Figure 1) to which a shifter 130 for the change speed gears 111, 112 is connected by a rod 131 connected to a second arm 132 on said rock shaft. To effect adjustment of the scale beam 119' simultaneously with the shifting of the change speed gears the rack 123 in mesh with the pinion of the scale beam is connected by a link 133 to the arm 126' movable with the hand lever 125.

To hold the roller 39 by means of which a portion of the conveyor is suspended from the weighing beam from movement in a direction longitudinally of the conveyor as the conveyor travels thereover with the possibility of exerting strains upon the weighing beam other than those effected by the load upon the conveyor as it travels over said roller a pair of restraining links 134 are provided one end of which links are connected to the roller supporting links 40 and the opposite ends connected to a fixed part of the framework (Figure 13). To prevent side swaying of said conveyor supporting roller 139 the roller supporting links 40 are extended beyond their connection with the roller and connected by a rod 135, said rod being pivotally connected intermediate its ends to one end of a rod 136 the opposite end of which rod is also connected to a fixed part of the framework.

To feed material in predetermined quantities from a source of supply to a place of use in proportional relation to another quantity of material fed to said place of use from another source of supply means are provided to intermittently actuate the conveyor B, which is effected by connecting the driving motor with the source of electricity and opening the circuit of the motor to stop the motor and conveyor after a predetermined length of travel of the conveyor. In Figure 24 there is diagrammatically illustrated feeding mechanism for this purpose wherein the feeding means hereinbefore described is represented in a general

way at D to deliver material to a place of use indicated as a bin E which may have a hopper outlet, and in feeding material to constitute one of the aggregates in cement making leading to a disintegrating apparatus (not shown). To feed another material or materials to the place of use E a second traveling conveyor is provided, designated in a general way by F and as of 10 of the belt type. The source of supply from which the material is being delivered is illustrated as being railway cars G from which the material is delivered to a hopper I having an outlet arranged to deliver material to the conveyor F.

The intermittent actuation of the conveyor mechanism D is controlled by the quantity of material fed by the conveyor F whereby to feed material by said conveyor 20 D proportional to the quantity of material fed by the conveyor F. For this purpose means are provided to determine the quantity of material fed by the conveyor F, which means is operative by the rate of 25 speed of travel of the conveyor and the load transported thereby. This means comprises a mechanical integrator of the type disclosed in Patent No. 954,870 granted to me April 12th, 1910, and illustrated in a 30 general way in Figure 25 and represented by J in Figure 24. As the construction and operation of this integrator mechanism is fully illustrated and described in my said patent detailed illustration and description 35 is not deemed to be necessary. This integrator includes a traveling element in the form of a belt and a rotary carrier in the form of a disk 137 carrying a series of integrating wheels upon its periphery to successively frictionally engage the traveling 40 element and the mounting for said carrier being arranged to adapt the carrier to turn in a plane parallel to the friction surface with mechanism to register the rotation of the disk or carrier for the integrating 45 wheels. When the disk has made a complete revolution a predetermined quantity of material will have been fed by the conveyor. The feeding means D is adapted to feed a 50 predetermined quantity of material which is proportional to the quantity of material fed by the feeding means F, and the feeding of material by the feeding means D is controlled by the quantity of material fed by 55 the feeding means F. For this purpose a time switch is provided to control the actuation of a switch, designated in a general way at T, for connecting the motor M into and cutting it out of circuit with a source of 60 electricity, the time switch being connected in circuit with electric circuit closing means forming a part of the integrator of the feeding means F. The circuit for closing the circuit of the time switch is diagrammatically illustrated in Figure 26.

The time switch comprises a series of three disks f, g and h of insulator material, such as fibre, and two pairs of contact heads 138, 138' and 139, 139', the heads 138, 138' being electrically connected and the 70 heads 139, 139' also being electrically connected. Each of said heads with the exception of head 139' is undercut or recessed at diametrically opposite points (indicated at h in Figure 26) to provide each of said 75 heads with what is in effect diametrically opposite arranged contact terminals; the head 139' has more than one-half of its circumference reduced to arrange said head in effect with a single contact terminal portion i. The contact head carrying disks are mounted on a shaft s rotatably supported in the walls of an enclosing housing for said switch mounted upon the supporting shelf 44 for the weighing beam. Contact terminals 140, 140' and 141, 141' are pivotally carried by brackets c fixed to and insulated from a bar 143 and yieldingly urged by springs d in a direction to contact with the head terminals h to have rubbing contact 80 therewith as clearly shown in Figure 22. The contact carrying shaft a is driven from the shaft 87 which is geared to and drives the drum rotating shaft 77 by a pinion 144 on shaft 87 meshing with a gear 145 on a 85 shaft 146 and having a pinion 147 fixed thereon meshing with a gear 148 on shaft s. The integrator disk 137 has a terminal contact 149 connected in circuit with a source of current supply, such as a battery 90 represented in a conventional manner at b and with which contact one of a pair of terminal contacts 151, 152 arranged diametrically opposite the axis of the integrator disk are adapted to contact. The contact 152 is electrically connected to the contact maker 141' by conductor j, while the contact 151 is electrically connected through conductor k to a contact maker 153 pivotally carried by a bracket o' fixed on and insulated from a bar 143' and urged to position in predetermined relation toward the contact head 139' by a spring d', said contact 153 being adapted to co-operate with the terminal i of contact head 139' to close the 100 circuit. The contact 141 is connected to one side of the source of current supply b by conductor l, the contact 149 of the integrator wheel being connected to the other side of the battery by a conductor m with an actuating coil 154 for a circuit closer 155' interposed therein. The circuit closer 155' is interposed in a conductor 156 connected to contact 140' and conductor m having a coil 157 of an electromagnetically operated circuit closer 157' interposed therein, said circuit closer being connected in the circuit of the motor M with a source of electric current supply. The contact 140' is 110 electrically connected through conductor l 120

with the course of current supply *b*, shown in the present instance for illustrative purposes through the contact 141 to conductor *n*. The circuit of the time switch is adapted to be closed upon each one-half revolution of the integrator wheel 137. Assuming that five hundred pounds is to be fed by the feeding means *D* to each two thousand pounds fed by the feeding means *F*.

10 Also assuming that contact is made between the contact head 139 and contact 141 as two thousand pounds is transported over the integrator by the feeding means *F* when contact head 149 of the integrator wheel will be brought into contact with the contact 152 closing the circuit for the time switch through the conductors *l*, *m* and contact 141 which is in contact with contact head 139, the latter as heretofore stated being 20 electrically connected with contact head 139', the closing of the circuit energizing coil 154 which actuates circuit closer 155 through contact 140' and the connection of the latter with the battery *b* by conductors *l* and 156 thereby actuating the circuit closing means 157, 157' and connecting the motor *M* in circuit with a source of electricity which motor operates the feeder means *B*, and as the limit switch is actuated 30 from said motor the switch will be actuated until the contact heads 138', 139, and 139' are positioned with the contacts 140', 141 and 141' engaging the undercut portions in said contact heads and out of contact there- 35 with opening the circuit through coil 154 when circuit closer 155' will move to circuit opening position shown in full lines. In order that the circuit may not be broken with a consequent stopping of the motor *M* 40 when the contact 149 of the integrating wheel moves out of contact with contact 152 and before the limit switch has completed a one-half revolution, a holding circuit is provided which is in the nature of a shunt 45 circuit connected in circuit with the conductors *l*, *m*, and comprising a conductor *o* connected with the conductor *m* at one terminal of coil 154 and with the contact 140 which co-operates with the contact head 138, 50 which, as stated, is electrically connected with the contact head 138', the conductor *o* being connected through said head and the contact 140' as hereinbefore described with the conductor *l*. The conductor *o* has a 55 circuit closer 155 connected therein which is connected with the circuit closer 155' to be actuated in unison therewith by the coil 154. This holding circuit will be broken simultaneously with the opening of the circuit through the contact heads 140', 141 and 141' by contact 140 coming opposite to an undercut portion of the contact head 138.

Should the integrating mechanism stop with the contact 149 in contact with contact 60 65 152 there will be no repetition of the feeder

mechanism *B* since upon the completion of a one-half revolution of the time switch contact heads contact will be broken through conductor 141' with the terminal contact *i* and contact head 139'. 70

Upon the feeding or delivery of a successive two thousand pounds by the feeding means *F* the integrator wheel 137 will be advanced a further one-half revolution bringing the contact 149 into contact with 75 contact 151 connected by conductor *h* with contact 153 when the circuit will be established through contact *i* of contact head 139' and contact 153 and the time switch in circuit with the conductor *m* when the circuit of the motor *M* is again established in a manner as hereinbefore described. The establishing of the circuit in this manner is 80 permissible since the area of the contact terminal portion *i* of contact head 139 is such that as it passes out of contact with contact 141' it is approaching contact 153 and sufficient momentum is given to the 85 feeder mechanism *B* even after the circuit of the driving motor *M* is broken to bring said contact terminal *i* into contact with the contact 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 - outlet arranged to deliver material to the conveyor, a weighing beam arranged with means for supporting a portion of the conveyor, adjustable means for regulating the area of the outlet of the hopper, and means operative independent of the weighing mechanism for actuating said regulating means for the hopper outlet controlled through the deflection of the weighing beam without imposing a stress upon and interfering with the movement of the weighing beam.
3. In apparatus for the purpose specified, a travelling conveyor, a hopper having an outlet for delivery of material from the hopper to said conveyor, adjustable means for regulating the delivery of material from the hopper, means for actuating said adjusting means, a weighing beam supporting portion of said conveyor, and means operable through the deflecting movement of the weighing beam imparted thereto by variations in the load carried by the portion of the conveyor supported by said beam to control the actuating means for the material delivery regulating means without imposing a stress and load upon the weighing beam.
4. In apparatus for the purpose specified, a travelling conveyor, a hopper having an outlet positioned for delivery of material from the hopper onto the conveyor, an adjustable closure for the hopper outlet, weighing mechanism arranged to support a portion of the conveyor, means to adjust the closure for the hopper outlet to regulate the area of the hopper outlet and delivery of material to the conveyor, and means to actuate said closure adjusting means controlled by the weighing mechanism as it is moved out of equilibrium by variations in the load upon the conveyor without interfering with the weighing mechanism or imposing a load thereon when the weighing mechanism is in equilibrium.
5. In apparatus for the purpose specified, a travelling conveyor, a hopper having an outlet positioned for delivery of material to the conveyor, adjustable closure means for the hopper outlet for regulating the delivery of material from the outlet, a weighing beam arranged with means to support a portion of the conveyor and having adjustable means to maintain it in equilibrium by a load of predetermined weight upon the conveyor, and means for actuating said adjustable closure means independently of and controlled from the weighing beam by movement thereof effected by variations in the weight of the load upon the conveyor to regulate the delivery of material to the conveyor from the hopper.
6. In apparatus for the purpose specified, a travelling conveyor, a hopper having an outlet for the delivery of material to the conveyor, a pivoted weighing beam arranged with means to support a portion of the conveyor, adjustable counterpoise to maintain the beam in equilibrium with a load of predetermined weight upon the conveyor, an adjustable closure for the hopper outlet, means to adjust the closure to regulate the discharge of material from the hopper, and means controlled by the movement of the weighing beam out of equilibrium by a variation in the weight of the load on the conveyor to operate the closure adjusting means without interfering with the movement of the beam and thereby maintain the delivery of material by the conveyor at a constant predetermined rate.
7. In apparatus for the purpose specified, a travelling conveyor, a hopper having an outlet positioned for delivery of material from the hopper to the conveyor, an adjustable closure for the hopper outlet, a pivoted weighing beam arranged to support a portion of said conveyor and maintained in equilibrium by a load of predetermined weight upon the conveyor, and means continuously operable independent of and controlled by the weighing beam when moved out of equilibrium without offering resistance to the movement of the beam operable to adjust the closure to vary the area of the hopper outlet to increase or decrease the quantity of material delivered from the hopper to the conveyor.
8. The combination with a travelling conveyor, of a hopper having an outlet for delivery of material from the hopper to the conveyor; a weighing beam arranged to support a portion of the conveyor therefrom and maintained in equilibrium by a load on the conveyor of a predetermined weight; and means to regulate the discharge of material from the hopper to the conveyor to compensate for a variation in the weight of the material on the conveyor, including a member movable longitudinally of the weighing beam controlled by the weighing beam when moved out of equilibrium by a variation in the load on the conveyor without interfering with the movement of or imposing a load upon the weighing beam extraneous to the force imposed on the beam by the load on the conveyor.
9. The combination of a hopper; a travelling conveyor to receive material delivered from the hopper; weighing mechanism including a weighing beam arranged to support a portion of the conveyor therefrom and having adjustable counterpoise to maintain the beam in equilibrium with a load of a predetermined weight upon the conveyor; and means to regulate the delivery of material to and maintain the load on the conveyor at such predetermined weight and delivery of material by the conveyor at a constant rate, including a member movable longitudinally of the weighing beam and the extent

and direction of such movement being controlled by the movement of the weighing beam to overload or underload position by variations in the load upon the conveyer.

- 5 10. The combination with a hopper having an outlet, of an adjustable closure for the hopper outlet; a travelling conveyer to receive material from the hopper; a weighing beam arranged to support a portion of the conveyer; adjustable counterpoise to maintain the beam in equilibrium by a predetermined load upon the conveyer; and means to adjust the closure for the hopper outlet to regulate the area thereof and discharge 15 of material from the hopper to the conveyer controlled by the deflection of the weighing beam out of equilibrium, comprising a continuously rotatable member adapted to have movement longitudinal of the weighing beam and having an operative connection with the closure to adjust the closure by longitudinal movement thereof, and a member to have frictional contact with said rotatable member and normally moving in a 20 direction at right angles to the axis of the rotatable member when the weighing beam is in equilibrium and the direction of movement of said member adapted to be changed in angular relation to the axis of the rotatable member by and in accordance with the deflection of the weighing beam effected by an increase or decrease of the load on the conveyer for the purpose specified.
- 25 11. The combination with a hopper having an outlet, of an adjustable closure for the hopper outlet; a travelling endless conveyer to receive material from the hopper; a weighing beam arranged to support a portion of the conveyer; a counterpoise to counterbalance a predetermined load upon the conveyer and maintain the beam in equilibrium; and means to adjust the closure for the hopper outlet to regulate the area 30 thereof controlled by the deflection of the weighing beam out of equilibrium by a variation in the weight of such predetermined load, comprising a pair of continuously rotatable members having an operative driving connection between the two, one of which 35 members is axially movable and having an operative connection with the closure for the hopper outlet, and the direction of travel of the other member being adapted to be changed in angular relation to the axis of the axially movable member by and in accordance with the deflection of the weighing beam.
- 40 12. The combination with a hopper having an outlet, of an adjustable closure for the hopper outlet; a travelling endless conveyer to receive material from the hopper outlet; a weighing beam arranged to support a portion of the conveyer; a counterpoise to counterbalance a load of a predetermined weight upon the conveyer and main-

tain the beam in equilibrium; and means to adjust the closure for the hopper outlet to regulate the area thereof controlled by the deflection of the weighing beam by a load under or over such predetermined weight upon the conveyer, comprising a to and fro longitudinally movable and continuously rotating member, connections from said member with the closure operable to move the closure to closing position when the member is moved in one direction and to move the closure to open position when the member is moved in an opposite direction, and a member frictionally driven from said longitudinally movable member controlled by the deflection of the weighing beam effected by a variation in the load on the conveyer, and operable to exert a thrust upon and move the longitudinally movable member longitudinally and direct such movement by and in accordance with the deflection of the weighing beam by an underload or overload upon the conveyer.

- 45 13. The combination with a hopper having an outlet, of an adjustable closure for the hopper outlet; a traveling endless conveyer to receive material from the hopper outlet; a weighing beam arranged to support a portion of the conveyer; a counterpoise to maintain the beam in equilibrium with a load of a predetermined weight upon the conveyer; and means to position the closure for the hopper outlet to regulate the area thereof controlled by the deflection of the weighing beam by a load under or over such predetermined weight upon the conveyer, comprising a to and fro longitudinally movable and continuously rotating member, a member frictionally driven from said rotatable member normally traveling at right angles to the axis of the rotatable member and holding the latter against longitudinal movement, said member having a connection with and adjustable by the deflection of the weighing beam through an overload or underload upon the conveyor to change the direction of movement of said frictionally driven member in angular relation to the axis of the rotatable member to exert a thrust upon and move said latter member longitudinally and control the direction of such movement, and a rack and gear connection between said rotatable and longitudinally movable member and the closure for the hopper outlet for the purpose specified.

- 50 14. The combination with a hopper having an outlet; of an adjustable closure for the hopper outlet; a traveling endless conveyer to receive material from the hopper outlet; a weighing beam arranged to support a portion of the conveyer; an adjustable counterpoise to maintain the beam in equilibrium with a load of a predetermined weight upon the conveyer; and means to ad-

- just the closure for the hopper outlet to regulate the area thereof controlled by the deflection of the weighing beam by a load under or over such predetermined weight upon the conveyer, comprising a rotatable drum supported to have to and fro axial movement, a disk frictionally driven from the drum normally maintained in position to rotate on an axis parallel with the axis of drum and in such position maintain the latter against longitudinal movement, means controlled by the deflection of the weighing beam to adjust the disk on an axis transverse to its axis of rotation to change the direction of travel of the disk in angular relation to the axis of the drum to exert a thrust upon and impart longitudinal movement to and control such movement of the drum, and a connection between said drum and closure for the hopper outlet.
15. The combination with a hopper having an outlet, of an adjustable closure for the hopper outlet; a traveling endless conveyer to receive material from the hopper outlet; a weighing beam arranged to support a portion of the conveyer and arranged with counterpoise weight to maintain the beam in equilibrium with a load of a predetermined weight upon the conveyer; and means to position the closure for the hopper outlet to regulate the area thereof controlled by the deflection of the weighing beam by a load under or over such predetermined weight upon the conveyer, comprising a rotatable drum supported to have to and fro longitudinal movement, a disk frictionally driven from the drum, a support for the disk adjustable with the disk on an axis transverse to the axis of rotation of the disk and arranged with means to normally maintain the same with the disk in position to rotate on an axis parallel with the axis of the drum, said disk support being adjustable by the deflection of the beam to change the direction of travel of the disk in angular relation to the axis of the drum to exert a thrust upon and move the drum longitudinally and control the direction of said movement, and a connection between said drum and the closure for the hopper outlet for the purpose specified.
20. The combination with a hopper having an outlet, of an adjustable closure for the hopper outlet; a traveling endless conveyer to receive material from the hopper outlet; a weighing beam arranged to support a portion of the conveyer and arranged with counterpoise weight to maintain the beam in equilibrium with a load of a predetermined weight upon the conveyer, comprising a rotatable drum mounted to have to and fro longitudinal movement, a disk frictionally driven from the drum and adjustable by the deflection of the beam to change the direction of travel thereof in angular relation to the axis of the drum to move the drum longitudinally and control the direction of said movement, a rack participating in the longitudinal movement of the drum, a gear meshing with the rack and movable to and fro by the movement of the rack, and a rack and pinion connection between said gear and closure for the hopper outlet for the purpose specified.
25. The combination with a hopper having an outlet, of an adjustable closure for the hopper outlet; a traveling endless conveyer to receive material from the hopper outlet; a weighing beam arranged to support a portion of the conveyer and maintained in equilibrium with a predetermined load upon the conveyer by counterpoise weight thereon; and means to position the closure for the hopper outlet to regulate the area thereof controlled by the deflection of the weighing beam by a load under or over such predetermined weight upon the conveyer, comprising a rotatable drum, carriages in which
30. said drum is journalled at opposite ends, tracks upon which the carriages are mounted to have longitudinal to and fro movement thereon with the drum, a disk frictionally driven from the drum and adjustable by the deflection of the beam to change the direction of travel thereof in angular relation to the axis of the drum operable to move the drum longitudinally and control the direction of such movement, and an operative connection between said drum and closure for the hopper outlet to position said closure by and in accordance with the movement of the drum to regulate the area of the hopper outlet for the purpose specified.
35. 17. The combination with a hopper having an outlet, of an adjustable closure for the hopper outlet; a traveling endless conveyer to receive material from the hopper outlet; a weighing beam arranged to support a portion of the conveyer and maintained in equilibrium with a predetermined load upon the conveyer by counterpoise weight adjustable on the beam; and means to position the closure for the hopper outlet to regulate the area thereof controlled by the deflection of the weighing beam by a load under or over such predetermined weight upon the conveyer, comprising a rotatable drum mounted to have to and fro longitudinal movement, a disk frictionally driven from the drum and adjustable by the deflection of the beam to change the direction of travel thereof in angular relation to the axis of the drum to move the drum longitudinally and control the direction of said movement, a rack participating in the longitudinal movement of the drum, a gear meshing with the rack and movable to and fro by the movement of the rack, and a rack and pinion connection between said gear and closure for the hopper outlet for the purpose specified.
40. 18. The combination with a traveling conveyer and a hopper having an outlet arranged to deliver material to the conveyer, of a weighing beam arranged to support a portion of the conveyer therefrom, adjustable poise weight to co-operate with the beam to counterbalance a load of predetermined weight upon the conveyer; an adjustable closure for the hopper outlet to vary the area thereof; and means to adjust and set the poise weight relative to the weighing beam and simultaneously with the adjustment and setting of the poise weight to set the closure for the hopper outlet to regulate the area thereof proportionally to the adjustment of the poise weight and lock the poise weight against movement relative to the beam while permitting adjustment of the closure for the hopper outlet and to vary the area of said outlet and delivery of material to the conveyer for the purpose specified.
45. 19. The combination with a traveling conveyer and a hopper having an outlet for de-

livery of material to the conveyer, of driving means for the conveyer; a weighing beam arranged with means to support a portion of the conveyer therefrom; adjustable counterpoise weight to counterbalance loads of variable weight supported by the beam; an adjustable closure for the hopper outlet to vary the area thereof; and means to set the counterpoise, the closure for the hopper outlet relative to said outlet and regulate the speed of travel of the conveyer in relation to each other.

20. The combination with a traveling conveyer and a hopper having an outlet for delivery of material to the conveyer, of a weighing beam arranged to support a portion of the conveyer therefrom; adjustable poise weight to co-operate with the beam to counterbalance a load of predetermined weight upon the conveyer; an adjustable closure for the hopper outlet to vary the area thereof; means to adjust and set the poise weight relative to the weighing beam and simultaneously therewith set the closure for the hopper outlet to regulate the area thereof proportional to the adjustment of the poise weight and lock the poise weight in adjusted position while permitting adjustment of the closure for the hopper outlet and delivery of material to the conveyer; and means to vary the speed of travel of the conveyer for the purpose specified.

21. The combination with a traveling conveyer and a hopper having an outlet for delivery of material to the conveyer, of a weighing beam arranged to support a portion of the conveyer therefrom; adjustable poise weight to co-operate with the beam to counterbalance a load of predetermined weight upon the conveyer; an adjustable closure for the hopper outlet to vary the area thereof; means to adjust and set the poise weight relative to the weighing beam and simultaneously therewith set the closure for the hopper outlet to regulate the area thereof proportional to the adjustment of the poise weight and lock the poise weight against movement relative to the beam while permitting adjustment of the closure for the hopper outlet and delivery of material to the conveyer; means to vary the speed of travel of the conveyer; and indicating means adjustable with the setting of the poise weight and closure for the hopper outlet to indicate the weight of the delivered load for the purpose specified.

22. The combination with a traveling conveyer and a hopper having an outlet for delivery of material to the conveyer, of a weighing beam arranged to support a portion of the conveyer therefrom, adjustable poise weight to co-operate with the beam to counterbalance a load of predetermined weight upon the conveyer; an adjustable closure for the hopper outlet to vary the

area thereof; and means to adjust and set the poise weight relative to the weighing beam and simultaneously therewith set the closure for the hopper outlet to regulate the area thereof proportionally to the adjustment of the poise weight, said means comprising a hand wheel, racks connected to the adjusting means for the poise weight and the closure, and a train of gearing to operatively connect the hand wheel with the racks.

23. The combination with a traveling conveyer and a hopper having an outlet for delivery of material to the conveyer, of a weighing beam arranged to support a portion of the conveyer therefrom; adjustable poise weight to co-operate with the beam to counterbalance a load of predetermined weight upon the conveyer; an adjustable closure for the hopper outlet to vary the area thereof; and means to adjust and set the poise weight relative to the weighing beam and simultaneously therewith set the closure for the hopper outlet to regulate the area thereof proportionally to the adjustment of the poise weight, said means comprising a hand wheel, racks connected to the adjusting means for the poise weight and the closure, a train of gearing including a gear in mesh with each of said racks to operatively connect the hand wheel with said racks, means to lock the hand wheel and gear in mesh with the poise weight adjusting rack against movement, and differential gearing interposed in the connection of the gear in mesh with the closure adjusting rack and the train of gearing to permit of independent adjustment of the closure for the hopper outlet to vary the area of said outlet and delivery of material to the conveyer from the hopper.

24. The combination with a traveling conveyer and a hopper having an outlet for delivery of material to the conveyer, of a weighing beam arranged to support a portion of the conveyer therefrom, adjustable poise weight to co-operate with the beam to counterbalance a load of predetermined weight upon the conveyer; an adjustable closure for the hopper outlet to vary the area thereof; and means to adjust and set the poise weight relative to the weighing beam and simultaneously therewith set the closure for the hopper outlet to regulate the area thereof proportionally to the adjustment of the poise weight, comprising a rotatable shaft having a hand wheel and a pair of gears thereon, a rack geared to one gear on said shaft and connected with the poise weight, a gear connected to the hopper closure, and gearing to operatively connect said rack with the other gear on the hand wheel shaft.

25. The combination with a traveling conveyer and a hopper having an outlet for de-

- livery of material to the conveyer, of a weighing beam arranged to support a portion of the conveyer therefrom, adjustable poise weight to co-operate with the beam to counterbalance a load of predetermined weight upon the conveyer; an adjustable closure for the hopper outlet to vary the area thereof; and means to adjust and set the poise weight relative to the weighing beam and simultaneously therewith set the closure for the hopper outlet to regulate the area thereof proportionally to the adjustment of the poise weight, and permit adjustment of the closure for the hopper outlet to vary the area of said outlet and delivery of material from the hopper, comprising a shaft having a hand wheel and a pair of gears mounted thereon, a slidably supported rack connected to the poise weight and geared to one of the gears on the hand wheel shaft, a rotatably supported and axially movable drum, a disk to frictionally contact with the drum normally rotating in a direction at a right angle to the axis of the drum with the beam in equilibrium and the direction of travel of said disk adapted to be varied in angular relation to the axis of the drum by and in accordance with the deflection of the beam and operative to exert a thrust upon the drum to move the same axially, a rack to participate in the axial movement of the drum, a rack connected to the closure, and differential gearing between the drum and closure racks and the other gear on the hand wheel shaft.
26. The combination with a traveling conveyer and a hopper having an outlet for delivery of material to the conveyer, of a weighing beam arranged with means to support a portion of the conveyer therefrom; adjustable poise weight to counterbalance a load of predetermined weight upon the conveyer; an adjustable closure for the hopper outlet to vary the area thereof; means controlled through the deflection of the beam by variations in the load on the conveyer operating to adjust the closure for the hopper outlet to vary the quantity of material delivered from the hopper and maintain the delivery of a load by the conveyer of a constant weight; and means to set the counterpoise weight relative to the weighing beam and simultaneously therewith set the closure for the hopper outlet to regulate the area thereof proportionally to the adjustment of the poise weight.
27. The combination with a traveling conveyer and a hopper having an outlet for delivery of material to the conveyer, of a weighing beam arranged with means to support a portion of the conveyer therefrom; adjustable poise weight to counterbalance a load of predetermined weight upon the conveyer; an adjustable closure for the hopper outlet to vary the area thereof; means con-
- trolled through the deflection of the beam by variations in the load on the conveyer operative to adjust the closure for the hopper outlet to vary the quantity of material delivered from the hopper and maintain the delivery of the load by the conveyer at a constant weight to deliver a predetermined quantity of material by the conveyer.
28. The combination with a traveling conveyer and a hopper having an outlet for delivery of material to the conveyer, of a weighing beam arranged with means to support a portion of the conveyer therefrom; adjustable poise weight to counterbalance a load of predetermined weight upon the conveyer; an adjustable closure for the hopper outlet to vary the area thereof; means operative from the conveyer to adjust the closure for the hopper outlet to vary the area of said outlet and the quantity of material delivered from the hopper to the conveyer; and means to control the actuation of said closure actuating means through the deflection of the beam by variations in the load on the conveyer.
29. The combination with a traveling conveyer and a hopper having an outlet for delivery of material to the conveyer, of a weighing beam arranged with means to support a portion of the conveyer therefrom; adjustable poise weight to counterbalance a load of predetermined weight upon the conveyer; an adjustable closure for the hopper outlet to vary the area thereof; means controlled through the deflection of the beam by variations in the load on the conveyer operative to adjust the closure for the hopper outlet to vary the quantity of material delivered from the hopper and maintain the delivery of the load by the conveyer of a constant weight; and means to yieldingly restrain the deflecting movements of the beam by a sudden increase or decrease of the load on the conveyer.
30. The combination with a traveling conveyer and a hopper having an outlet for delivery of material to the conveyer, of a weighing beam arranged with means to support a portion of the conveyer therefrom; adjustable poise weight to counterbalance a load of predetermined weight upon the conveyer; an adjustable closure for the hopper outlet to vary the area thereof; means controlled through the deflection of the beam by variations in the load on the conveyer operating to adjust the closure for the hopper outlet to vary the quantity of material delivered from the hopper to the conveyer and maintain the delivery of the load by the conveyer of a constant weight; and an auxiliary counterpoise weight supported independent and normally free of the beam and adapted to be automatically applied to the beam when the beam is deflected beyond a pre-

terminated point by the sudden increase or decrease of the load on the conveyer.

31. The combination with a traveling conveyer and a hopper having an outlet for delivery of material to the conveyer, of a weighing beam arranged with means to support a portion of the conveyer therefrom; adjustable poise weight to counterbalance a load of predetermined weight upon the conveyer; an adjustable closure for the hopper outlet to vary the area thereof; means controlled through the deflection of the beam by variations in the load on the conveyer operating to adjust the closure for the hopper outlet to vary the quantity of material delivered to the conveyer and maintain the delivery of the load by the conveyer of a constant weight; an auxiliary counterpoise weight supported independent and normally free of the beam and adapted to be automatically applied to the beam when the beam is deflected beyond a predetermined point by the sudden increase or decrease of the load on the conveyer; and a dash pot having connection with the beam to prevent undue vibration of the beam when brought to point of perfect balance by the load upon the conveyer.
32. The combination of a traveling conveyer, a hopper having an outlet with an adjustable closure for delivery of material to the conveyer, a weighing beam arranged with means to support a portion of the conveyer therefrom with a load of predetermined weight carried thereby; means controlled through the deflection of the beam by variations in the load on the conveyer operating to adjust the closure for the hopper outlet to vary the quantity of material delivered from the hopper to the conveyer and maintain the delivery of the load by

the conveyer of a constant weight; and pendulum weight supported independent and normally free of the beam adapted to be automatically connected to the beam when the beam is deflected beyond a predetermined point above or below the horizontal for the purpose specified.

33. The combination of a traveling conveyer, a hopper having an outlet with an adjustable closure for delivery of material to the conveyer, a weighing beam arranged with means to support a portion of the conveyer therefrom; adjustable poise weight to counterbalance a load of predetermined weight upon the conveyer; means controlled through the deflection of the beam by variations in the load on the conveyer operating to adjust the closure for the hopper outlet to vary the quantity of material delivered to the conveyer and maintain the delivery of the load by the conveyer of a constant weight; and pendulum weight supported independent and normally free of the beam adapted to be automatically connected to the beam when the beam is deflected beyond a predetermined point above or below the horizontal, comprising a pivotal support, levers having weights connected thereto to normally maintain the levers in position with the weights below the center of gravity, a rod suspended from the beam arranged with means to engage with one of said levers when the beam is moved to position below the horizontal and to engage the other lever when the beam is moved to position above the horizontal.

Signed at New York city in the county of New York and State of New York this 1st day of August, 1924.

HERBERT L. MERRICK.
